UNITED STATES PATENT OFFICE.

BENEDICT S. BADURA, OF LINCOLN, NEBRASKA.

GRANARY DOOR.

Application filed June 1, 1926. Serial No. 113,059.

The invention aims to provide a new and improved door for granaries, provided with a pair of wings, and downwardly swingable to an open position. Thus, when a wagon 5 is driven alongside of the granary to either load or unload the grain, the door may be downwardly swung to the edge of the wagon bed and the wings may be extended, so that a wide platform is provided between the 10 granary and the wagon, preventing any grain from being thrown onto the ground, during the act of shoveling it either into or from the wagon.

A further object of the invention is to 15 provide a carrying frame for the door, which is of such nature that it may be quickly and easily secured to a granary, and will maintain a tight, weatherproof connection therewith.

With the foregoing in view, the invention resides in the novel subject matter hereinafter described and claimed, the description being supplemented by the accompanying drawing.

Figure 1 is an outer side elevation of the invention in operative relation with a wagon.

Figure 2 is a vertical transverse section on line 2—2 of Fig. 1.

Figure 3 is a horizontal section on the plane of line 3—3 of Fig. 1.

Figure 4 is a front elevation showing the door in its closed position.

Figures 5 and 6 are respectively vertical 35 and horizontal sections on lines 5—5 and 6—6 of Fig. 4.

The numeral 8 on the accompanying drawing, designates a door frame which is preferably formed from metal, said frame 40 having a portion 9 to lie against the outer side of a granary 10, around an opening 11, said frame being also provided with another portion 12 to enter the opening 11. This portion 12 is provided with an inwardly extending flange 13, and a door 14 45 which is preferably formed from metal, closes against the outer side of said flange, the door being hinged at its lower end as indicated at 15, so that it may swing downwardly to a position at which it outwardly 50 declines from the granary. Any desired fastening means 16 may be provided for normally holding the door in closed position.

55 A pair of rectangular side wings 17 are hinged at 18 to the door 14, and said wings

are folded against the inner side of said door as shown in Figs. 4, 5 and 6 when this door is closed. However, when the door is swung outwardly to permit grain to be 60 either thrown into or out of the granary 10 the wings 17 may be laterally extended from the door 14, as shown in Figs. 1, 2 and 3. Thus, a platform substantially three 65 times as wide as the door 14, is provided to extend between the door opening and the wagon W to be loaded or unloaded, and this platform preferably declines to said wagon, so that any grain falling upon it will slide back into the wagon bed. When 70 the platform is thus declined, it will be seen that the inner edges of the wings 17 will strike the side members of the frame 8, when said wings are outwardly swung to extend in position. Thus, the wings are 75 limited in their downward swinging. These wings and the door 14 may either rest directly upon the edge of the wagon bed, or may be supported a desired distance above 80 said bed, by means of an appropriate leg 19 which is pivoted to the door 14.

In order that the frame 8 may be quickly and easily attached, I prefer to provide two or more bolts 20 passing through the frame portion 9, the inner ends of said bolts having 85 hooks 21 to engage two-by-fours 22 at the sides of the opening 11, the outer ends of said bolts being provided with nuts 23 which may be tightened for the purpose of 90 securely clamping the frame to the building. This frame may either be shaped for contact with a flat-sided building or with one having a cylindrical form, and when tightly 95 clamped in place, will be proof against entrance of rain. In this connection, attention may be invited to the fact that a suitable water shed 24 is preferably provided at the upper end of the frame. Attention is 100 also invited to the fact that as the door 14 is mounted within the confines of the frame 8, there is no danger of strong wind ripping it from its hinges.

As excellent results may be obtained from the details disclosed, they are preferably followed. However, within the scope of the 105 invention as claimed, variations may be made.

I claim:—

1. A device of the class described comprising a door frame, a door hinged thereto for 110 downward and outward swinging to a position at which it projects from the lower end

of said frame, and a pair of side wings hinged to said door and projectable laterally therefrom beyond the side members of the frame when said door is in its downwardly and outwardly swung position, said wings being overlapped at the inner side of the door when the latter is closed.

2. A device of the class described comprising a door frame, a door hinged thereto for downward and outward swinging to a position at which it declines from the lower end of the frame, and a pair of side wings hinged to said door and projectable laterally therefrom beyond the side members of the frame when said door is in its downwardly and outwardly swung position, the inner ends of said wings being then adapted to abut said side members of the frame to limit the

downward and outward swinging thereof, said wings being overlapped at the inner 20 side of the door when the latter is closed.

3. In a device of the class described, a frame having one portion to contact with the side of a building around an opening, and having another portion to enter the opening, bolts passing through the first named frame portion at the outer side of said other portion, the inner ends of said bolts having hooks to engage frame members of the building, and nuts on the outer 30 ends of said bolts for tightening them to secure the frame tightly in place.

In testimony whereof I have hereunto affixed my signature.

BENEDICT S. BADURA.
